UNITED STATES PATENT OFFICE

125,642

DESIGN FOR A BUILDING BLOCK

Frank P. Pandolfi, Buffalo, N. Y.

Application August 2, 1940, Serial No. 94,159

Term of patent 7 years

To all whom it may concern:

Be it known that I, Frank P. Pandolfi, a citizen of the United States, residing at Buffalo, in the county of Erie and State of New York, have invented a new, original, and ornamental Design for Building Blocks, of which the following is a specification, reference being had to the accompanying drawing, forming part thereof.

Fig. 1 is a perspective view of a building block showing my new design.

Fig. 2 is a longitudinal section through the building block taken on line 2—2, Fig. 1.

I claim:

The ornamental design for a building block, as shown.

FRANK P. PANDOLFI.
